ATOMIZER

Joy B. Schmitt and William R. Dodds, Toledo,
Ohio, assignors to The De Vilbiss Company,
Toledo, Ohio, a corporation of Ohio

Application February 15, 1943, Serial No. 476,014

4 Claims. (Cl. 299—88)

This invention relates to atomizers designed particularly for the application of medicinal preparations but which are suitable for applying other liquids as well. An important object of our invention is the provision of an atomizer for applying a measured quantity of a liquid preparation and one that is capable of discharging the entire amount of such preparations whether it is composed of a few drops or several drams.

A second important object of the invention is to provide a well balanced atomizer with a single piece body portion.

Still another object of our invention is to provide an atomizer in which the liquid preparation flows through the bottom of the container to the discharge tube, and one so constructed that no liquid will leak from the nozzle when the atomizer is in its ordinary upright position.

Other important objects of our invention will be apparent from a reading of the following description in connection with the drawing wherein, for purposes of illustration, we have shown a preferred embodiment of our invention.

In the drawing

Fig. 1 is a side elevation of the embodiment;

Fig. 2 is a longitudinal sectional view taken through Fig. 1;

Fig. 3 is a section of the atomizer nozzle taken on a line 3—3 of Fig. 2; and

Fig. 4 is a section of the air and liquid tubes taken on a line 4—4 of Fig. 2.

Referring in detail to the drawing, the atomizer has a main body portion 1 which has an upper cuplike cavity 2 for holding the medicine. This is closed by cap piece 3. Integral with the body is a conical supporting apron 4 upon which the atomizer rests. Through the body portion 1 is an inclined passage 5. Into this from one side is inserted air nipple 6, to the outer end of which is fastened air bulb 7. At the rear of the air bulb 7 is an air check valve 8 of conventional design, permitting the entrance of air into the bulb when the bulb expands and preventing a flow of air out through the valve on compression of the bulb. In the front end of nipple 6 is pressed a long air tube 9.

To the same end of the nipple 6 extending through the body 1 is threaded a liquid tube 10 which is made in two parts for manufacturing expedience. This tube is positioned in surrounding relation to the tube 9. The air tube 9 is round in section for its whole length up to its tip where it is flattened on three sides as shown in Fig. 3, providing three grooves for the fluid

to pass through to reach the nozzle discharge opening 11 at the end of tube 10.

After the proper amount of the medicinal preparations has been introduced into the receptacle portion 2 by dropper or other means, the cover 3 may be put in place to prevent spilling. This cover 3 should either fit loosely enough to provide a slight space for air to enter the cup or should have a small vertical groove in the skirt portion to act as a vent passage. If it follows the natural flow induced by gravity, at least some of the medicament will pass down from the cup through the port 12 to angular groove 13 in the air nipple 5. From this groove 13 two opposed passages 14 extend to the longitudinal passage 15. From here the medicine will flow up toward the discharge opening 11 through the extension of passage 15 to a point within tube 10 where it is level with the surface of the medicinal preparation remaining in cup 2.

The tube 10 is so inclined upwardly that its top point is level with the top of cup 2. This prevents the liquid from flowing out of tip 11 when the atomizer is in its normal upright position. When it is desired to use the atomizer, the tip is inserted into the mouth or nasal cavity, whichever is to be treated, and the bulb 7 is compressed. Air will travel through tube 9 and out the discharge nozzle 11 creating a suction effect for drawing the medicinal liquid up the tube 10 and out of the discharge port 11. The mixture of air and liquid occurring at port 11 results in the atomization of the liquid.

The general design of the atomizer makes it compact. The bottom outlet of the receptacle permits the drainage of all medicine therefrom. This is not possible from the ordinary atomizer which has an outlet tube extending down into its receptacle. Some medicine is ordinarily left beneath the end of such outlet tubes.

The one piece body portion is inexpensive to manufacture and provides a fine supporting base for the bulb on one side and the discharge tube on the other without any threaded engagement directly with either of them.

The bulb and air assembly by threaded engagement with the tube 10 is held against body portion 1. Nipple 5 fits tightly into the body, thereby preventing any leak of the liquid.

Although we have shown and described herein in a preferred embodiment of our invention, it is definitely to be understood that we do not desire to limit the application of the invention thereto, and various changes may be made in the structure and arrangement of parts without

departing from the spirit of our invention and avoiding the scope of the following claims.

We claim:

1. In an atomizer for applying a single dose of medicine or the like, a body piece having a cuplike cavity at its top and a similar inverted cavity at its bottom, the upper cup forming a receptacle for the medicine and the bottom edge of the bottom cup forming the supporting base for the atomizer, an inclined passage through the center of the body portion between the cups, a nipple extending through the passage from its lower end, an air bulb fastened to the outer end of the nipple on one side of the atomizer body, an elongated nozzle fastened to the other end of the nipple from the other side of the atomizer body and extending therefrom in an upward direction, and an outlet opening on the bottom of the medicine cup forming a communicating passage from the cup to the nipple.

2. In an atomizer for spraying medicinal preparations a body portion, a receptacle associated therewith for the preparation, an upwardly inclined bore through the body, a vertical passage into the bore communicating with the receptacle, an outwardly facing shoulder at each end of the bore, an air supply nipple extending into the bore from its lower end and seating against the shoulder at that end, an elongated liquid discharge tube extending from the opposite end of the bore and held against the shoulder at that end through a connection with the air supply nipple, a passage in the air supply nipple for delivering the preparation to the liquid discharge tube and an extension of the air supply nipple extending cen-

trally into and through the liquid discharge tube to carry air to the discharge end of said tube.

3. An atomizer for spraying medicinal preparations and the like, comprising a body, a receptacle of restricted size in the upper portion of the body with an outlet in its bottom, an elongated nozzle having communication with the receptacle outlet and extending in a straight line from the body below the receptacle to a point above the normal level of the liquid in the receptacle, a flaring supporting base integral with the body and an air supply bulb fastened to the body on the opposite side of, but in line with the elongated discharge nozzle and having communication with the nozzle to supply it with atomizing air.

4. In a medicinal atomizer of the type described, a body, a receptacle for medicine attached to the body, a transverse bore through the body, an outwardly facing shoulder at each end of the bore, an air supply nipple seating against one of the shoulders, an elongated discharge nozzle held against the other shoulder by a connection through the bore with the air supply nipple, an elongated air tube fastened to the nipple and extending therefrom through the bore and centrally into and toward the outer end of the discharge nozzle, a passage between the receptacle and the bore to deliver medicine to the nozzle, and an air bulb connected to the nipple for supplying atomizing air through the air tube to the nozzle.
